UNITED STATES PATENT OFFICE.

CHARLES J. MILLER, OF MINNEAPOLIS, MINNESOTA, ASSIGNOR TO GEBHARD C. BOHN,
OF ST. PAUL, MINNESOTA.

ICE-CRUSHER.

1,112,464.

Specification of Letters Patent.

Patented Oct. 6, 1914.

Application filed March 30, 1908. Serial No. 424,267.

To all whom it may concern:

Be it known that I, CHARLES J. MILLER, of Minneapolis, Hennepin county, Minnesota, have invented certain new and useful Improvements in Ice-Crushers, of which the following is a specification.

The object of my invention is to provide an ice-crushing device for domestic use or for supplying the crushed ice used in connection with soda fountains and ice-cream parlors, and the object of the invention is to provide a small compact device capable of being hung on the wall and by means of which a piece of ice can be easily and quickly reduced to a crushed condition.

The invention consists generally in various constructions and combinations, all as hereinafter described and particularly pointed out in the claims.

20 In the accompanying drawings, forming part of this specification, Figure 1 is a top view of an ice-crusher embodying my invention. Fig. 2 is a vertical sectional view illustrating the construction of the same. Fig. 3 25 is a vertical sectional view on the line α — α of Fig. 2. Fig. 4 is a front view of the device.

In the drawing, 2 represents a plate having key hole slots 3 therein to receive screws 30 4 which are inserted into the wall. The lower end of the plate has a series of notches 5 to receive similar screws for holding the plate securely against the wall.

6 represents side plates or guards hinged 35 to the back plate at 7, if preferred, to allow them to swing into the plane of the back plate against the wall, or these side plates may be rigidly mounted, if preferred. A strap 8 extends across the space between the 40 side plates and forms a stop for a lever 9 secured to a plate 10 that is pivoted at 11 on a bail 12 that is secured to said back plate and projects outwardly therefrom.

The plate 2 is provided with a fixed 45 crusher plate 13 removably secured by bolts 14 and having a series of teeth 15 formed thereon. These teeth taper to a point and are arranged sufficiently near together to thoroughly crush the ice introduced between them and the movable crushing plate 10 having a series of similar teeth 16, and to which plate 10 the lever 9 is secured. The teeth of these plates coöperate with one another to thoroughly crush the ice introduced between

them, the length of the teeth preferably decreasing from the top toward the bottom of the crusher.

In Fig. 2 I have illustrated a modification which consists in providing teeth 17 that are punched or pressed out of the plates, the metal being of sufficient thickness to form rigid teeth that will be capable of crushing the ice introduced between them. The crusher plates may have key-hole slots 18, as illustrated in Fig. 3 to allow the plates to be easily and quickly mounted on their supports or removed.

I have shown the side guards 6 made of wood but do not confine myself to this material as I may find sheet metal more desirable for certain places where the crusher is to be used.

To hold the movable crusher plate in its raised or vertical position I provide a hook 19 secured to the rear wall plate and adapted to be swung outwardly therefrom to engage the handle 9.

To use the device the ice is put in at the top with a suitable receptacle arranged beneath on the floor and the operator grasping the handle 9 and forcing it inwardly toward the wall will bring the crusher teeth into co-operating relation with one another and cause the rapid and uniform reduction of the ice.

The device may be made in different sizes and is adapted for use wherever it is desired to crush ice for domestic or other purposes.

I claim as my invention:

1. An ice crusher comprising a plate having means for attachment to a wall, a series of teeth mounted on said plate and projecting outwardly therefrom, side plates hinged to said wall plate and adapted to swing back against the wall into the plane of said wall plate or move outwardly to a position parallel with one another and at right angles substantially to said wall plate, means for temporarily securing said hinged plates in a position parallel with one another, and a lever hinged at its lower end near said wall plate, a plate carried by said lever and fitting between said hinged plates, a series of teeth mounted on said lever plate, and the lower end of said lever being spaced a sufficient distance from said wall plate to permit the discharge of the crushed ice therethrough, substantially as described.

2. An ice crusher comprising a rear plate, side plates attached at their rear edges to said rear plate, a plate hinged at its lower end intermediate of said side plates, a strap normally connecting the outer portions of said side plates and holding them in parallel position, said strap serving as a stop to limit the movement of said hinged plate, a hand lever carried by said hinged plate and a plu-

rality of teeth extending toward each other 10 from said back and hinged plates.

In witness whereof, I have hereunto set my hand this 26th day of March 1908.

CHARLES J. MILLER.
